UNITED STATES PATENT OFFICE.

WILLIAM F. MARTIN, OF BALDWINSVILLE, NEW YORK, ASSIGNOR TO PENN SPRING WORKS INC., OF BALDWINSVILLE, NEW YORK, A CORPORATION OF NEW YORK.

DESIGN FOR AN AUTOMOBILE BUMPER PLATE.

Application filed March 20, 1924. Serial No. 9,008. Term of patent 14 years.

To all whom it may concern:

Be it known that I, WILLIAM F. MARTIN, a citizen of the United States, residing at Baldwinsville, New York, have invented a new, original, and ornamental Design for Automobile Bumper Plate, of which the following is a specification, reference being had to the accompanying drawing, forming part thereof.

The drawing is a perspective view of an automobile bumper plate showing my new design.

What I claim is:

The ornamental design for an automobile bumper plate as shown.

WILLIAM F. MARTIN.
